CURTAIN DRAWING DEVICE

Filed March 18, 1931

Inventors.

Johann Peter Schmidt, Jr.

UNITED STATES PATENT OFFICE

JOHANN PETER SCHMIDT, JR., OF REMSCHEID-DORFMUHLE, GERMANY

CURTAIN DRAWING DEVICE

Application filed March 18, 1931, Serial No. 523,449, and in Germany December 27, 1930.

This invention relates to a curtain-drawing device and consists in the combination with a flanged supporting rail and with curtain suspending elements adapted to ride on the flange of said rail, of a slide which snugly embraces the rail flange and which is formed with a tongue adapted to enter the suspending elements for collecting the latter on the slide.

10 The slide may either be composed of a plate which is folded in conformity with the shape of the rail flange or of a wire which is looped and bent to embrace the flange.

15 For use on curved supporting rails, the slide may be made flexible or composed of pivotally connected links.

Fig. 1 of the accompanying drawing represents a side view of one form of the device,

20 Fig. 2 is a cross section on the line A—B of Fig. 1,

Fig. 3 is a perspective view of part of the slide,

25 Figs. 4 to 6 are views of differently constructed suspending elements,

Fig. 7 is a perspective view of the device,

30 Figs. 8 and 9 are cross sectional views of different modifications of the device,

Fig. 10 is a perspective view of the device shown in Fig. 9,

35 Figs. 11 and 12 are cross sectional views of further modifications of the device,

Fig. 13 is a perspective view of a device comprising a jointed slide,

40 Fig. 14 is a bottom view of a device provided with a jointed slide of modified construction,

Fig. 15 is a top view of a device comprising a wire slide,

45 Fig. 16 is a cross section of Fig. 15,

Fig. 17 is a top view of a device comprising a modified form of wire slide, and

Fig. 18 is a top view of a device comprising a still further modified form of wire slide.

45 The curtain-drawing device comprises a flanged supporting rail 1, a plurality of curtain suspending elements 4 adapted to ride on the rail flange and for this purpose provided either with integral bearing members 5 or attached bearing members 6, and a slide 2 whereon said suspending elements can be

collected, the bearing members 5, 6 being rounded off to enable them to move easily from the rail flange on to the slide. The slide is operated in the usual manner by means of cords which are connected to eyelets 8. At the forward end of the slide a tongue 3 is provided which is adapted to enter the suspending elements and guide them on to the slide.

55 In the arrangement shown in Figs. 1 to 7 the slide is made from a thin sheet metal strip which is folded over at the edges for engagement with the flange of a T-rail. The eyelets 8 shown in Figs. 1 and 2 may be replaced by a yoke 8a connected to the underside of the slide as shown in Fig. 7.

60 Fig. 8 shows a sheet metal slide 2a fitted to an L-shaped supporting rail 1a, and Figs. 9 and 10 show a slide 2b fitted to the lower portion of a rail 1b of C-shaped cross section.

65 In Fig. 11, a sheet metal slide 2c is bent so as to fit a T-rail 1c the flange of which is formed with upturned edges, and Fig. 12 shows a slit tubular supporting rail 1d which encloses a forked sheet metal slide 2d which is bent around the edges of the slit.

70 In Fig. 13, a sheet metal slide 2e is bent so as to fit a T-rail 1e the flange of which is formed with upturned edges, and Fig. 14 shows a modification of this arrangement is shown in Fig. 14 80 wherein links 9a are pivoted to a connecting strip 10 which is flexible to allow the slide to pass from a straight rail portion on to a curved one and vice versa.

75 Fig. 15 shows a slide 7 made from a wire 85 which is looped and bent over the rail flange. A similar arrangement is shown in Fig. 17 where the wire slide 7a is bent to fit a curved rail.

80 Fig. 18 shows a slide comprising two parallel, cylindrical coil springs 11 which are interconnected under the rail flange by cross pieces 12. Intermediate cross pieces 12a, connected alternately to opposite springs, bear against the underside of the rail flange 95 and form controlling elements for the springs. This kind of slide can be used either for straight or for curved rails.

I claim:—

1. A curtain-drawing device comprising a 100

flanged supporting rail, curtain suspending elements adapted to ride on the flange of said rail, a slide arranged on the underside of the rail and snugly embracing the rail flange, and a tongue at one end of said slide adapted to enter the suspending elements for collecting the latter on the slide.

2. A curtain-drawing device as claimed in claim 1 wherein the slide consists of a plate which is folded in conformity with the rail flange.

3. A curtain-drawing device as claimed in claim 1 wherein the slide comprises a wire which is looped and bent to embrace the rail flange.

4. A curtain-drawing device as claimed in claim 1 wherein the slide is composed of pivotally connected links.
